LASTING MACHINE

Eric A. Holmgren, Lynn, Mass., assignor to United
Shoe Machinery Corporation, Paterson, N. J.,
a corporation of New Jersey

Application June 11, 1937, Serial No. 147,723

25 Claims. (Cl. 12—4)

This invention relates to lasting machines, and has particularly in view the provision of improved means for lasting the heel ends of welt shoes. It has been proposed heretofore to defer the lasting 5 of the heel ends of shoes of this type until after the welts have been attached to the shoes, and a further object of the invention is to provide improved means for lasting the heel ends of shoes in that condition. In various novel aspects, however, 10 the invention is not limited in utility to the lasting of previously welted shoes or, in fact, to the lasting of shoes of the welt type, and in certain aspects, moreover, it is not limited to the lasting of the heel ends of shoes.

With the above and other objects in view, the invention, in accordance with one feature, provides novel wiping means the range of the wiping action of which in a direction lengthwise of the shoe may be varied for shoes of different sizes. In lasting the heel ends of welt shoes this permits the margin of each upper to be wiped inwardly over the insole as far forwardly as the ends of the lip of the insole regardless of differences in the length of the heel seat in shoes of different sizes. The construction shown comprises end wipers which are movable lengthwise and laterally of the shoe to wipe the margin of the upper inwardly throughout a portion only of the length of the heel seat, and side wipers arranged to wipe the margin of the upper inwardly at the sides of the heel seat beyond the end wipers and movable laterally of the shoe relatively to the end wipers with components of movement toward the toe end of the shoe to extend the range of their wiping action lengthwise of the shoe a distance dependent upon the size of the shoe. In the illustrated embodiment of the invention the end wipers and the side wipers are supported on the same wiper carriers which are operated by a hand lever, and it is contemplated that this hand lever will preferably be used first to move all the wipers a certain distance lengthwise and laterally of the shoe in wiping engagement with the margin of the upper, this movement of the wipers being limited by a stop. Thereafter, by another hand lever, the side wipers will be further moved relatively to the end wipers as and for the purpose above described, their movements being adjustably limited in accordance with the size of the shoe. By the use of the first-mentioned hand lever all the wipers will then be further advanced and closed to complete the overwiping operation, this movement also being limited to avoid any danger of damaging the lip of the insole. To permit the upper to be

fastened in lasted position without retracting the wipers, the end wipers are provided with holes through which tacks may be driven by a hand tacker and the side wipers have slots for the same purpose, these slots being arranged in angular relation to one another to space the tacks substantially equal distances apart in any positions of the side wipers at the end of their wiping movements.

To improve the results obtained in lasting the heel ends of welt shoes, the invention further provides novel means for applying inwardly directed tightening force to the previously lasted upper adjacent to the forward end of the heel seat. For this purpose the construction shown comprises plates which in operating on a previously welted shoe are carried idly into the welt crease as all the wipers are first operated in the manner above described and are then adjustably positioned in accordance with the size of the shoe as the side wipers are moved relatively to the end wipers, the plates being thereafter forced inwardly to tighten the upper adjacent to the heel seat as all the wipers are further operated to complete the overwiping operation. These plates may further serve as means to support the welt while the operator butts its ends by use of a hand knife prior to the driving of the lasting tacks.

The above and other features of the invention, including various novel details of construction and combinations of parts, will now be more particularly described with reference to the accompanying drawings and thereafter pointed out in the claims.

In the drawings,

Fig. 1 is a perspective view of a portion of a machine in which the invention is embodied;

Fig. 2 is a plan view of a portion of the structure shown in Fig. 1, with parts broken away;

Figs. 3, 4 and 5 are plan views illustrating the positions of the wipers and associated parts at different times in the lasting operation;

Fig. 6 is a section on the line VI—VI of Fig. 2;

Fig. 7 is a perspective view illustrating the butting of the welt;

Fig. 8 is a diagrammatic plan view illustrating different positions of the wipers in operating on shoes of different sizes; and

Fig. 9 is a section on the line IX—IX of Fig. 2.

For illustrative purposes the invention is herein shown as applied to a bed-lasting machine of a well-known type the construction of which is disclosed, in its general aspects, in United States Letters Patent No. 1,018,477, granted on February 27, 1912, upon an application of Matthias Brock.

Only as much of such a machine is included in the drawings as is necessary for an understanding of the invention. The machine is provided with a support 2 for the heel end of the last and shoe, having a spindle (not shown) which enters the spindle hole in the last, and with a toe rest, also not shown, for supporting the last and shoe at the forepart. The shoe is firmly clamped about its heel end in the lasting operation by a heel band 4. For wiping the margin of the heel end of the upper inwardly over the insole there are provided heel-embracing wipers 6 pivotally connected together by a stud 8, these wipers in the construction herein shown being so short that in operating on shoes of different sizes they wipe each upper inwardly throughout a portion only of the length of the heel seat. The wipers 6 are secured to wiper carriers 10 which are movably supported on a wiper head 12 (Fig. 1) and over which there is a cover plate 14 fastened to the wiper head. The wiper carriers 10 are connected by links 16 to a crossbar 18 operated through a plunger 20 by means of a hand lever 22, and they are controlled as heretofore by guiding means including rolls 24 mounted on studs 26 and lying in slots 28 in the carriers. Accordingly, as the hand lever 22 is operated the wipers 6 are advanced lengthwise of the shoe and are also closed inward laterally of the shoe by swinging about the axis of their pivotal connection 8. By means hereinafter described the rolls 24, in the construction herein shown, are adjustable to vary the starting positions of the wipers for shoes of different sizes.

To determine with substantial accuracy the relation of the bottom of the heel end of the shoe to the plane of the wipers, there is secured to the cover plate 14, in the construction herein shown, a bracket 30 which supports two holdown members 32 and 34 arranged to engage the insole respectively at the heel end and in a location a short distance forwardly of the heel end. An upwardly extending shank portion of the member 32 is vertically adjustable in a bore in the bracket 30, as shown in Fig. 7, and is engaged at its upper end by a screw 36 threaded in the bracket to determine adjustably the height of the holdown member. A set screw 38 in the bracket engages a flat face on the shank portion of the member 32 to prevent the member from turning and from dropping below the screw 36. The holdown member 34 is similarly controlled by an adjusting screw 40 and a set screw 42.

The wiper carriers 10 in the construction herein shown are extended to serve also as supports for side wipers 44 arranged to wipe the margin of the upper inwardly over the insole at the sides of the heel seat beyond the end wipers 6, the lower wiping faces of the side wipers being in the same plane as the lower faces of the end wipers. The side wipers 44 are mounted in guideways in the carriers 10, as illustrated in Fig. 6, to permit them to be moved inwardly over the heel seat relatively to the end wipers, these guideways being so formed that the side wipers are thus movable rectilinearly widthwise of the shoe with components of movement lengthwise of the shoe toward its toe end. The inner end portions of the side wipers are wedge-shaped in plan, so that at the end of the wiping operation their foremost edges 45 (Fig. 5) will be approximately perpendicular to the edge of the shoe bottom, and accordingly the range of their wiping action lengthwise of the shoe increases in proportion to the extent of their inward movements relatively to

the end wipers. For operating the side wipers there are provided two levers 46 and 48 pivotally mounted between their opposite ends on bolts 50 secured to the wiper head 12, the upper ends of these bolts being braced by a plate 52 secured by a bolt 54 to a cap plate 56 fast on the wiper head. The inner arms of the two levers 46 and 48 are connected together by a link 58. Each of the levers has an arm 60 arranged to extend generally lengthwise of the shoe and provided with a slot 62 in which lies a stud 64 fast on the outer end of the adjacent side wiper 44. The lever 46 has a handle 66 thereon for operating it. It will be understood that by movement of the handle 66 toward the left (Fig. 1) both levers 46 and 48 are operated to cause their arms 60 to swing inwardly toward each other and thus to impart inward movements to the side wipers 44 while the end wipers 6 are stationary. The slots 62 are curved in such manner as to permit the side wipers to be moved lengthwise and laterally of the shoe with the end wipers, when the wiper carriers 10 are operated by the hand lever 22, without any substantial relative movement between the end wipers and the side wipers adjacent thereto, the studs 64 moving idly along the slots. It is contemplated that preferably all the wipers will thus be operated in unison at the beginning of the lasting operation, with the side wipers so retracted that their inner wiping edges are in substantial alignment with the wiping edges of the end wipers, as shown in Fig. 2. In this movement the wipers are advanced and closed over the heel seat a portion only of the distance required for the complete wiping operation, their movement being limited by engagement of a pin 68 (Fig. 1) on the hand lever 22 with a shoulder 70 on a bar 72 pivotally mounted at one end on a stud 74 on the cap plate 56. The bar 72 is connected by a link 76 to a hand grip 78 which is pivotally mounted on the lever 22 and is controlled by a spring 80. This spring holds the bar 72 against the pin 68, which normally lies in a slot in one side of the bar, and by engagement of the pin with a shoulder on the bar at the opposite end of this slot from the shoulder 70 retractive movement of the wipers is limited as illustrated in Fig. 1. It will be evident that after the initial advancing and closing movement of the wipers has been stopped by engagement of the pin 68 with the shoulder 70, the operator, by means of the hand grip 78, can swing the bar 72 away from the pin 68 so as to permit further advancing and closing movement of the wipers by the lever 22. Prior to this further movement of all the wipers the operator moves the side wipers 44 inward relatively to the end wipers, to vary the range of their wiping action lengthwise of the shoe in accordance with the size of the shoe, by use of the hand lever 46. The further movement of all the wipers thereafter by the lever 22 is limited by engagement of the head of a bolt 82 with the wiper head 12, this bolt being mounted in a block 84 through which the lever 22 is connected to the outer end of the plunger 20. As the bolt 82 engages the wiper head 12 the pin 68 enters a notch 86 in the side of the bar 72 to lock the wipers against retractive movement while tacks are driven to fasten the upper in lasted position as hereinafter described.

The inward movements of the side wipers 44 effected by use of the hand lever 46 are adjustably limited in accordance with the size of the shoe. For this purpose there is associated with 75

each of the side wipers a slide 88 connected to the stud 64 and extending inwardly over the top of the wiper carrier 10. This slide is guided by a pin 90 fast on the wiper carrier and extending upwardly through a slot 92 in the slide, the pin having a diametrically enlarged portion 94 which assists in supporting the slide underneath. In engagement with the lower face of the slide 88 is a plate 96 (Fig. 6) provided with a rib 98 extending upwardly into the slot 92, and this plate is clamped adjustably to the slide by a screw 100 the head of which overlaps a plate 102 on the top of the slide. The plate 102 is held from turning relatively to the plate 96 by a pin 104 extending upwardly from the plate 96 into a hole in the plate 102. As shown in Fig. 2, there is marked on the slide 88 a scale graduated in shoe sizes, and the plate 102 has a pointer to indicate by reference to this scale the proper adjustment of the plate 96 for each size of shoe. By engagement with the pin 90 the plate 96 then limits the inward movement of the side wiper 44 relatively to the adjacent end wiper 6 as determined for the particular size of shoe. It will be understood that this adjustment is such that in the final movement of all the wipers by the lever 22 each side wiper will be advanced lengthwise of the shoe into the proper close relation to the end of the lip α of the insole.

It will be evident from the foregoing description that the amount of operative movement which the end wipers 6 receive is always the same regardless of the size of the shoe. As far as the advancing movement of the wipers lengthwise of the shoe is concerned, satisfactory results are thus obtained in operating on shoes of different sizes, since the heel band 4 determines a substantially invariable position for the heel-end faces of the different shoes. With respect to the closing of the wipers, however, the wiping edges of the wipers 6 at the opposite sides of the heel seat should, of course, approach more closely to each other in operating on a small shoe than in operating on a larger shoe. The machine herein shown is accordingly provided with means for effecting an initial adjustment of the wiper carriers 10 about the axis of closing movement of the wipers in accordance with the size of the shoe by moving the rolls 24 toward or away from each other. By reference to Fig. 9, it will be seen that the studs 26 on which these rolls are mounted extend through slots in the cover plate 14 and in the overlying base plate 106 of the bracket 30 and are integral with blocks 108 supported on the top of the plate 106. Mounted to turn in the bracket 30 is a spindle 110 held against lengthwise movement by collars 112 fast thereon at the opposite sides of the bracket, this spindle having right and left threads engaging corresponding threads formed respectively in the two blocks 108. On one end of the spindle is a hand wheel 114 for turning it. The two blocks 108 are further guided by a rod 116 fastened in the bracket and lying in slots in the upper ends of the blocks. It will thus be seen that by turning the spindle 110 in one direction the rolls 24 are moved farther apart to adjust the wiper carriers 10 and their wipers 6 for a shoe of smaller size and that by turning the spindle in the other direction the rolls are moved toward each other to adjust the carriers and wipers for a shoe of larger size. The proper adjustment for a shoe of any size is indicated by a scale 118 (Fig. 1) marked on the plate 106 in cooperation with a pointer marked on one of the

blocks 108. It will be evident that the side wipers 44 also are adjusted in this manner with the end wipers 6.

In operating on previously welted shoes it is desirable to tighten the upper over the last in locations where the welt b is attached adjacent to the forward end of the heel seat before the upper is fastened in lasted position at the sides of the heel seat. Each of the wiper carriers 10 is accordingly provided with a plate 120 having a comparatively thin tongue 122 arranged to enter the welt crease forwardly of the adjacent side wiper 44. By means of a rod 124 this plate is pivotally mounted on a small plate 126 located under the wiper carrier 10 and lying in a rectangular recess in the plate 120. This permits limited upward or downward swinging movement of the plate 120 so that its tongue 122 may adjust itself to the welt crease. The plate 126 is provided with an upwardly extending rib 128 which lies in a slot 130 in the wiper carrier 10, and parallel to this slot is another slot 132 in the wiper carrier in which lies a roll 134 mounted on a stud 136 threaded at its lower end in the plate 126. The stud 136 extends upwardly through a small plate 138 which lies on the top of the wiper carrier under one end of the previously mentioned slide 88, and also extends through a slot 140 in this slide, the stud being provided with an enlarged head overlapping a washer 142 on the top of the slide 88. The plates 126 and 138 are further held in a definite relation to each other by a pin 144 extending from the rib 128 into a hole in the plate 138. The slots 130 and 132 are so arranged as to guide the plates 126 and 138, together with the welt crease plate 120 supported on the plate 126, for movements laterally of the shoe relatively to the wiper carrier 10 with components of movement also lengthwise of the shoe. Accordingly, when the slide 88 is advanced to move the side wiper 44 forwardly and inwardly as determined for the size of the shoe, the crease plate 120 is correspondingly positioned lengthwise and laterally of the shoe by movement diagonally forward and outward with respect to the shoe, so that in the final movement of the wipers to complete the overwiping operation inwardly directed upper-tightening force will be properly applied to the shoe in the welt crease.

In order that the upper may be fastened in lasted position without retracting the wipers, the end wipers 6 are provided with holes 146 to receive the nozzle of the usual hand tacker and the side wipers 44 are provided for the same purpose with slots 148. The slots in each side wiper are arranged in outwardly divergent relation to one another so as to space the tacks substantially equal distances apart in operating on a shoe of any size, and the slot which is nearest the end of the lip of the insole is also so arranged that the corresponding tack will always be located close to the end of the lip. Further to insure that the side wipers will press the margin of the upper materials firmly down on the insole, each end wiper 6 has a projection 150 overlying the adjacent side wiper, this projection having a slot therein over one of the slots 148 in the side wiper to receive the nozzle of the hand tacker. Before driving the tacks the operator may butt the ends of the welt by use of a hand knife 152 (Fig. 7), the welt being supported against the thrust of the knife by the tongues 122 of the plates 120. It will be evident that the foremost edges 45 of the side wipers 44

assist the operator in determining where to make the cuts in the welt.

In the use of the machine the operator first adjusts the wiper carriers 10 in accordance with 5 the size of the shoe by turning the spindle 110 and also adjusts the stop plates 96 to the proper positions for that size of shoe. He then mounts a shoe on the shoe support 2, jacks the shoe back against the heel band 4 and upwardly, and causes 10 the heel band to close about the heel end of the shoe, in the well-known manner of use of bed-lasting machines of the illustrated type. As the shoe is forced upwardly it engages the two hold-down members 32 and 34 which determine the 15 proper relation of the heel seat to the plane of the heel wipers. The operator next swings the lever 22 to the position determined by engagement of the pin 68 with the shoulder 70, thus advancing and closing all the wipers to the positions illustrated in Fig. 3. In this operation the 20 tongues 122 of the crease plates 120 are moved to positions under the ends of the welt but not far enough to apply any tightening force to the upper. By use of the hand lever 46 the side wipers 25 44 are then moved inward relatively to the end wipers 6 to positions determined by engagement of the stop plates 96 with the pins 90 on the wiper carriers. The side wipers are thus caused to approach the ends of the lip of the insole as determined by the size of the shoe, so that in the 30 final wiping operation they will be advanced substantially to the ends of the lip, and simultaneously the crease plates 120 are moved in diagonally forward and outward directions to 35 position them also in accordance with the size of the shoe. The positions of the parts at the end of this operation are as illustrated in Fig. 4. The operator thereafter disengages the pin 68 from the shoulder 70 by use of the hand grip 78 40 and further swings the lever 22 to the limit determined by engagement of the bolt 82 with the wiper head 12, thus advancing and closing all the wipers to complete the overwiping operation, as illustrated in Fig. 5, the pin 68 entering the 45 notch 86 in the bar 72 to lock the wipers against retractive movement. In this operation the tongues 122 of the crease plates 120 are forced fully into the welt crease to tighten the upper over the last forwardly of the heel seat. By use 50 of the hand knife 152 the operator then butts the ends of the welt, after which he drives upper-fastening tacks through the holes 146 in the end wipers and the slots 148 in the side wipers. All the parts are then returned to their starting 55 positions ready for use on the next shoe.

In Fig. 8 are illustrated different positions of the wipers in operating respectively on a shoe of size 5 and on a shoe of size 12, the positions of the tacks driven through the slots 148 in the side 60 wipers 44 being indicated at t.

It will be understood that a machine constructed as described may be used, if desired, to last the heel ends of welt shoes prior to the welt-attaching operation, in which case the 65 crease plates 120 will press inwardly against the upturned margin of the upper opposite the end portions of the insole lip with a tightening effect on the upper forwardly of the heel seat. Furthermore, it will be evident that with respect to 70 the combination of end and side wipers controlled as described for use on shoes of different sizes the invention is not limited in utility to the lasting of welt shoes nor necessarily limited to the lasting of the heel ends of shoes.

75 Having described the invention, what I claim

as new and desire to secure by Letters Patent of the United States is:

1. In a lasting machine, wipers formed to embrace the heel end of a shoe and movable lengthwise and laterally of the shoe to wipe the margin of the upper inwardly throughout a portion only of the length of the heel seat, side wipers for wiping the margin of the upper inwardly at the sides of the heel seat beyond said end wipers, the side wipers being movable relatively to the end wipers to vary the range of their wiping action lengthwise of the shoe, and means for thus moving the side wipers relatively to the end wipers in the course of the wiping operation on each shoe a distance dependent upon the size of the shoe but predetermined independently of contact with the shoe. 10 15

2. In a lasting machine, wipers formed to embrace the heel end of a shoe and movable lengthwise and laterally of the shoe to wipe the margin of the upper inwardly throughout a portion only of the length of the heel seat, side wipers for wiping the margin of the upper inwardly at the sides of the heel seat beyond said end wipers, the side wipers being movable laterally of the shoe 20 25 relatively to the end wipers with components of movement toward the toe end of the shoe to extend the range of their wiping action lengthwise of the shoe, and means for thus moving the side wipers relatively to the end wipers a distance dependent upon the size of the shoe each time a shoe is lasted in the machine. 30

3. In a lasting machine, wipers formed to embrace the heel end of a shoe and movable lengthwise and laterally of the shoe to wipe the margin of the upper inwardly throughout a portion only of the length of the heel seat, side wipers for wiping the margin of the upper inwardly at the sides of the heel seat beyond said end wipers, the side wipers being movable relatively to the end wipers to vary the range of their wiping action lengthwise of the shoe, means for thus moving the side wipers relatively to the end wipers each time a shoe is lasted in the machine, and stop mechanism for adjustably limiting such movement of the side wipers in accordance with the size of the shoe. 35 40 45

4. In a lasting machine, wipers formed to embrace the heel end of a shoe and mounted for advancing movement lengthwise of the shoe and swinging movement laterally of the shoe to wipe the margin of the upper inwardly throughout a portion only of the length of the heel seat, side wipers mounted to advance and swing with said end wipers and arranged to wipe inwardly portions of the margin of the upper at the sides of the heel seat beyond the end wipers, the side wipers being movable relatively to the end wipers to vary the range of their wiping action lengthwise of the shoe, and means for thus moving the side wipers relatively to the end wipers a distance dependent upon the size of the shoe each time a shoe is lasted in the machine. 50 55 60

5. In a lasting machine, wipers formed to embrace the heel end of a shoe and mounted for advancing movement lengthwise of the shoe and swinging movement laterally of the shoe to wipe the margin of the upper inwardly throughout a portion only of the length of the heel seat, side wipers mounted to advance and swing with said end wipers in wiping engagement with portions of the margin of the upper at the sides of the heel seat beyond the end wipers, the side wipers being also movable laterally of the shoe relatively to the end wipers with components of 65 70 75

movement toward the toe end of the shoe to extend the range of their wiping action lengthwise of the shoe, and means for thus moving the side wipers relatively to the end wipers a distance dependent upon the size of the shoe each time a shoe is lasted in the machine.

6. In a lasting machine, wipers formed to embrace the heel end of a shoe and mounted for advancing movement lengthwise of the shoe and 10 swinging movement laterally of the shoe to wipe the margin of the upper inwardly throughout a portion only of the length of the heel seat, additional wedge-shaped wipers mounted to advance and swing with said end wipers and arranged 15 to wipe inwardly portions of the margin of the upper at the sides of the heel seat beyond the end wipers, said additional wipers being movable relatively to the end wipers to vary the range of their wiping action lengthwise of the 20 shoe, and means for thus moving the additional wipers relatively to the end wipers a distance dependent upon the size of the shoe each time a shoe is lasted in the machine.

7. In a lasting machine, wipers formed to embrace the heel end of a shoe and movable lengthwise and laterally of the shoe to wipe the margin of the upper inwardly throughout a portion only of the length of the heel seat, wiper carriers supporting said end wipers and thus movable with them, side wipers supported on said wiper carriers independently of the end wipers to move with the end wipers lengthwise and laterally of the shoe in wiping engagement with portions of the margin of the upper at the sides 35 of the heel seat beyond the end wipers, the side wipers being movable also relatively to the end wipers to vary the range of their wiping action lengthwise of the shoe, and means for thus moving the side wipers relatively to the end wipers 40 a distance dependent upon the size of the shoe each time a shoe is lasted in the machine.

8. In a lasting machine, wipers formed to embrace the heel end of a shoe and movable lengthwise and laterally of the shoe to wipe the margin of the upper inwardly throughout a portion only of the length of the heel seat, wiper carriers supporting said end wipers and thus movable with them, side wipers supported on said wiper carriers to move with the end wipers in wiping engagement with portions of the margin of the upper at the sides of the heel seat beyond the end wipers, the side wipers being also rectilinearly movable laterally of the shoe relatively to the end wipers with components of movement 55 toward the toe end of the shoe to extend the range of their wiping action lengthwise of the shoe, and means for thus moving the side wipers relatively to the end wipers a distance dependent upon the size of the shoe each time a shoe is lasted in the machine.

9. In a lasting machine, wipers formed to embrace the heel end of a shoe and mounted for advancing movement lengthwise of the shoe and swinging movement laterally of the shoe to wipe the margin of the upper inwardly throughout a portion only of the length of the heel seat, side wipers mounted to advance and swing with said end wipers in wiping engagement with portions of the margin of the upper at the sides of the 65 heel seat beyond the end wipers, means for thus operating all the wipers in unison, the side wipers being also movable relatively to the end wipers to vary the range of their wiping action lengthwise of the shoe, and additional means for thus moving the side wipers relatively to the end 70 wipers a distance dependent upon the size of the shoe each time a shoe is lasted in the machine.

wipers a distance dependent upon the size of the shoe each time a shoe is lasted in the machine.

10. In a lasting machine, wipers formed to embrace the heel end of a shoe and mounted for advancing movement lengthwise of the shoe and 5 swinging movement laterally of the shoe to wipe the margin of the upper inwardly throughout a portion only of the length of the heel seat, side wipers mounted to advance and swing with said end wipers in wiping engagement with portions 10 of the margin of the upper at the sides of the heel seat beyond the end wipers, means for limiting such movement of all the wipers, the side wipers being also movable relatively to the end wipers to vary the range of their wiping action lengthwise of 15 the shoe, and means for thus moving the side wipers relatively to the end wipers a distance dependent upon the size of the shoe after the movement of all the wipers to positions determined by said limiting means, all the wipers being thereafter further movable in unison to complete the 20 wiping operation.

11. In a lasting machine, wipers formed to embrace the heel end of a shoe and mounted for advancing movement lengthwise of the shoe and 25 swinging movement laterally of the shoe to wipe the margin of the upper inwardly throughout a portion only of the length of the heel seat, side wipers mounted to advance and swing with said end wipers in wiping engagement with portions 30 of the margin of the upper at the sides of the heel seat beyond the end wipers, means for thus imparting to all the wipers in unison a movement to begin the wiping operation and later a further movement to complete the wiping operation, 35 means for limiting each such movement of the wipers, the side wipers being also movable relatively to the end wipers to vary the range of their wiping action lengthwise of the shoe, means for thus moving the side wipers between the two 40 movements of all the wipers, and means for adjustably limiting such movement of the side wipers in accordance with the size of the shoe.

12. In a lasting machine, wipers formed to embrace the heel end of a shoe and movable lengthwise and laterally of the shoe to wipe the margin of the upper inwardly throughout a portion only of the length of the heel seat, and side wipers for wiping the margin of the upper inwardly at the sides of the heel seat beyond said end wipers, 45 the side wipers being movable laterally of the shoe relatively to the end wipers with components of movement also lengthwise of the shoe to vary the range of their wiping action lengthwise of the shoe in accordance with the size of the shoe and 50 each having therein slots arranged to extend laterally of the shoe in divergent relation to one another to permit fastenings to be driven through them into the upper substantially equal distances apart regardless of the size of the shoe. 55

13. In a lasting machine, wipers formed to embrace an end of a shoe and movable lengthwise and laterally of the shoe to wipe the margin of the upper inwardly, side wipers for wiping the margin of the upper inwardly at the sides of the 65 shoe beyond said end wipers, the side wipers being movable lengthwise and laterally of the shoe with the end wipers and also movable relatively to the end wipers to vary the range of their wiping action lengthwise of the shoe, and means for 70 thus moving the side wipers relatively to the end wipers to adjustably predetermined positions each time a shoe is lasted in the machine.

14. In a lasting machine, wipers formed to embrace an end of a shoe and movable lengthwise 75

and laterally of the shoe to wipe the margin of the upper inwardly, side wipers for wiping the margin of the upper inwardly at the sides of the shoe beyond said end wipers, the side wipers being movable with the end wipers and also movable laterally of the shoe relatively to the end wipers with components of movement lengthwise of the shoe to vary the range of their wiping action lengthwise of the shoe, means for thus moving the side wipers relatively to the end wipers each time a shoe is lasted in the machine, and stop mechanism for adjustably limiting such movement of the side wipers.

15. In a lasting machine, wipers formed to embrace an end of a shoe and mounted for advancing movement lengthwise of the shoe and swinging movement laterally of the shoe to wipe the margin of the upper inwardly, side wipers for wiping the margin of the upper inwardly at the sides 20 of the shoe beyond said end wipers, the side wipers being mounted to advance and swing with the end wipers and being also inwardly movable laterally of the shoe relatively to the end wipers with components of movement lengthwise of the 25 shoe in directions away from the end wipers, and means for thus moving the side wipers relatively to the end wipers in operating on each shoe.

16. In a lasting machine, wipers formed to embrace an end of a shoe and movable lengthwise 30 and laterally of the shoe to wipe the margin of the upper inwardly, wiper carriers supporting said end wipers and thus movable with them, side wipers for wiping the margin of the upper inwardly at the sides of the shoe beyond said end 35 wipers, the side wipers being supported on said wiper carriers independently of the end wipers to move with the end wipers and being also inwardly movable laterally of the shoe relatively to the end wipers with components of movement lengthwise 40 of the shoe in directions away from the end wipers, and means for thus moving the side wipers relatively to the end wipers in operating on each shoe.

17. In a lasting machine, wipers formed to 45 embrace an end of a shoe and mounted for advancing movement lengthwise of the shoe and swinging movement laterally of the shoe to wipe the margin of the upper inwardly, side wipers for wiping the margin of the upper inwardly at 50 the sides of the shoe beyond said end wipers, the side wipers being mounted to advance and swing with the end wipers and being also inwardly movable laterally of the shoe relatively to the end wipers with components of movement lengthwise 55 of the shoe in directions away from the end wipers, a lever for advancing and swinging all the wipers, and another lever for moving the side wipers relatively to the end wipers.

18. In a lasting machine, wipers formed to 60 embrace the heel end of a previously side-lasted welt shoe and movable lengthwise and laterally of the shoe to wipe the margin of the upper inwardly throughout a portion only of the length of the heel seat, side wipers for wiping the margin of 65 the upper inwardly at the sides of the heel seat beyond said end wipers, the side wipers being movable relatively to the end wipers to vary the range of their wiping action lengthwise of the shoe in accordance with the size of the shoe, members for engaging the previously lasted upper 70 opposite the insole lip to tighten the upper over the last forwardly of the heel seat, and means for adjusting said members in accordance with the size of the shoe as determined by the movements 75 of the side wipers relatively to the end wipers.

19. In a lasting machine, wipers formed to 5 embrace the heel end of a previously side-lasted welt shoe and movable lengthwise and laterally of the shoe to wipe the margin of the upper inwardly throughout a portion only of the length of the heel seat, side wipers for wiping the margin of the upper inwardly at the sides of the heel seat beyond said end wipers, the side wipers being movable relatively to the end wipers to vary the range of their wiping action lengthwise 10 of the shoe, means for thus moving the side wipers relatively to the end wipers a distance dependent upon the size of the shoe each time a shoe is lasted in the machine, members for engaging the previously lasted upper opposite the insole lip 15 to tighten the upper over the last forwardly of the heel seat, and connections between said members and the side wipers for adjusting said members in accordance with the size of the shoe as determined by the movements of the side wipers 20 relatively to the end wipers.

20. In a lasting machine, wipers formed to 25 embrace the heel end of a previously welted shoe and movable lengthwise and laterally of the shoe to wipe the margin of the upper inwardly 25 throughout a portion only of the length of the heel seat, side wipers for wiping the margin of the upper inwardly at the sides of the heel seat beyond said end wipers, the side wipers being movable laterally of the shoe relatively to the end 30 wipers with components of movement also lengthwise of the shoe to vary the range of their wiping action lengthwise of the shoe in accordance with the size of the shoe, members for engaging the shoe in the welt crease to tighten the upper 35 over the last forwardly of the heel seat, and means for adjusting said members lengthwise and laterally of the shoe in accordance with the size of the shoe as determined by the movements of the side wipers relatively to the end wipers. 40

21. In a lasting machine, wipers formed to 45 embrace the heel end of a previously welted shoe and movable lengthwise and laterally of the shoe to wipe the margin of the upper inwardly throughout a portion only of the length of the heel seat, side wipers for wiping the margin of the upper inwardly at the sides of the heel seat beyond said end wipers, the side wipers being movable with the end wipers and also movable relatively to the end wipers to vary the range 50 of their wiping action lengthwise of the shoe in accordance with the size of the shoe, members also movable with said end wipers for engaging the shoe in the welt crease to tighten the upper over the last forwardly of the heel seat, and means for adjusting said members in accordance with the size of the shoe as determined by the movements of the side wipers relatively to the end wipers. 55

22. In a lasting machine, wipers formed to 60 embrace the heel end of a previously welted shoe and movable lengthwise and laterally of the shoe to wipe the margin of the upper inwardly throughout a portion only of the length of the heel seat, side wipers for wiping the margin of 65 the upper inwardly at the sides of the heel seat beyond said end wipers, the side wipers being movable with the end wipers and also movable laterally of the shoe relatively to the end wipers with components of movement lengthwise of the 70 shoe to vary the range of their wiping action lengthwise of the shoe, means for thus moving the side wipers relatively to the end wipers a distance dependent upon the size of the shoe in operating on each shoe, members movable with 75

the end wipers for engaging the shoe in the welt crease to tighten the upper over the last forwardly of the heel seat, and means for adjusting said members lengthwise and laterally of the
5 shoe in accordance with the size of the shoe as determined by the movements of the side wipers relatively to the end wipers.

23. In a lasting machine, wipers formed to embrace the heel end of a previously welted shoe 10 and movable lengthwise and laterally of the shoe to wipe the margin of the upper inwardly throughout a portion only of the length of the heel seat, side wipers for wiping the margin of the upper inwardly at the sides of the heel seat 15 beyond said end wipers, the side wipers being movable with the end wipers and also movable inward laterally of the shoe relatively to the end wipers with components of movement lengthwise of the shoe to extend the range of their wiping 20 action lengthwise of the shoe in accordance with the size of the shoe, members movable with the end wipers for engaging the shoe in the welt crease to tighten the upper over the last forwardly of the heel seat, and connections between said 25 members and the side wipers for adjusting said members in outward directions laterally of the

shoe in accordance with the size of the shoe with components of movement also lengthwise of the shoe as determined by the movements of the side wipers relatively to the end wipers.

24. In a lasting machine, wipers movable to 5 wipe the margin of the heel end of the upper of a previously welted shoe into lasted position, and members movable with said wipers for engaging the shoe in the welt crease to tighten the upper over the last forwardly of the heel seat, said members 10 being mounted for movements heightwise of the shoe relatively to the wipers to permit them to adjust themselves to the welt crease.

25. In a lasting machine, wipers movable to 15 wipe the margin of the heel end of the upper of a previously welted shoe into lasted position, and members movable with said wipers for engaging the shoe in the welt crease to tighten the upper over the last forwardly of the heel seat, said members 20 being each mounted to swing heightwise of the shoe relatively to the wipers about an axis extending laterally of the shoe to permit them to adjust themselves to the welt crease.

ERIC A. HOLMGREN. 25
